UNITED STATES PATENT OFFICE

LEE S. CHADWICK, OF SHAKER HEIGHTS, AND CHARLES J. KESSLER, OF CLEVELAND HEIGHTS, OHIO, ASSIGNORS TO PERFECTION STOVE COMPANY, OF CLEVELAND, OHIO, A CORPORATION OF OHIO

DESIGN FOR A HEATER

Application filed July 7, 1931. Serial No. 40,453. Term of patent 14 years.

To all whom it may concern:

Be it known that we, LEE S. CHADWICK and CHARLES J. KESSLER, citizens of the United States, residing at Shaker Heights and Cleveland Heights, respectively, in the county of Cuyahoga and State of Ohio, have invented a new, original, and ornamental Design for Heater, of which the following is a specification, reference being had to the accom-

panying drawings, forming part hereof, wherein Figures 1 and 2 are front and rear perspective views, respectively, of a heater showing our new design.

We claim:

The ornamental design for a heater, as shown.

LEE S. CHADWICK.
CHARLES J. KESSLER.
